UNITED STATES PATENT OFFICE.

PAUL E. DEMMER, OF SAN JOSE, CALIFORNIA, ASSIGNOR TO D. & W. SPECIALTY COMPANY, A CORPORATION.

BREAKER MECHANISM FOR DISTRIBUTORS.

Application filed March 2, 1923. Serial No. 622,281.

To all whom it may concern:

Be it known that I, PAUL E. DEMMER, a citizen of the United States, residing at San Jose, county of Santa Clara, State of California, have invented certain new and useful Improvements in Breaker Mechanism for Distributors; and I do declare the following to be a full, clear, and exact description of the same, reference being had to the accompanying drawings, and to the characters of reference marked thereon, which form a part of this application.

This invention relates to improvements in the breaker mechanisms of timers or distributors such as are generally used in the ignition systems of internal combustion engines.

The principal object of my invention is to provide a breaker mechanism, applicable to any form of distributor, so constructed that a rubbing action is had between the contact points of the breaker when they come together or separate, making it impossible for the points to pit or burn, and of course increasing the life thereof.

Another object is to construct the said mechanism so that the breaking distance, or the spacing between the breaker points when they are separated, will be the same at all times, regardless of the wear of the points or of any play or wobbling movement of the shaft which carries the breaker actuating cam.

This latter feature insures sparks of equal intensity being formed at the plugs of all the cylinders of an engine at all times, regardless of the looseness of the cam shaft or distributor head, eliminating the necessity of fitting said shaft with new bearings on that account or of replacing the distributor head.

The contact points may also be adjusted to break the right distance before the device leaves the factory, and need not be disturbed thereafter.

A further object of the invention is to produce a simple and inexpensive device, and yet one which will be exceedingly effective for the purposes for which it is designed.

These objects I accomplish by means of such structure and relative arrangement of parts as will fully appear by a perusal of the following specification and claim.

In the drawings similar characters of ref-

erence indicate corresponding parts in the several views.

Fig. 1 is a front view of a distributor, showing my improved breaker mechanism with the points closed or in contact.

Fig. 2 is a similar view, showing the contact points separated.

Fig. 3 is a cross section taken on the line 3—3 of Fig. 1, the cam shaft being removed.

Referring now more particularly to the characters of reference on the drawings, the numeral 1 denotes the distributor head or casing of a type particularly intended for use on the engine of a certain popular make of car, this casing having a transverse wall 2 intermediate its ends, said wall having a central orifice 2^a.

Mounted on the outer or front face of this wall in suitable spaced relation are rigidly fixed L-shaped brackets 3, one of which is in direct contact with said wall while the other is insulated therefrom.

Rigidly fixed on the brackets are flat spring strips 4, which extend past the orifice 2^a on opposite sides thereof and therebeyond for a certain distance, being symmetrically bent toward each other as at 5 for the latter portion of their extent, being again made straight or parallel to each other at their outer ends.

These springs lie parallel to the wall 2, with their greatest width at right angles thereto.

At the outer ends of the springs 4, which take the place on the usual movable and fixed breaker arms, are mounted contact points 6, one of which at least is adjustable relative to its arm, any suitable means, such as shown at 7, being used to accomplish this.

Fixed on the inner faces of the arm 4 and facing each other are lugs 8 of fiber or some similar insulation material, these lugs being diametrically disposed relative to the axis of the cam shaft 9 of the engine, which when the distributor is assembled, projects through the orifice 2^a, and carries a fixed cam 10 having a plurality of opposed high and low faces 11 and 12 respectively, as is customary.

These faces and the lugs 8 are so arranged relative to each other that when any two of the low faces 12 are adjacent the lugs, the latter are clear of the same, and the springs 4 are still in tension, the points 6 being then in contact.

- Due to the symmetrical curvature in the arms 4, as at 5, when the points 6 come into contact with each other under the spring tension present throughout the length of the 5 arms, the upper or free ends of said arms have a tendency to move longitudinally. This tendency is occasioned by the tendency of the spring tension curvatures 5 to straighten outer under the pressure of the 10 contacting points. This action imparts a slight and consistent wiping or rubbing effect on the points in both directions as they are moved into or out of contact with each other. 15 The same action, but in the reverse direction, is of course obtained when the contacts are separated, the result being that the points cannot pit or burn, as happens when they are moved directly away from each other without any such rubbing. 20 The breaking of the contacts is had when the high faces 11 of the cam engage the lugs 8, and it will be evident that since the distance between any two opposed faces is a 25 fixed quantity, the amount the points are to be separated will always be the same, regardless of whether one arm may be sprung or moved outwardly a greater amount than the other, as would be the case if the shaft 30 and casing were out of true relative to each other, and as happens when the shaft is running in a too free bearing, or the casing becomes loose. The latter conditions, when the usual single movable breaker arm is 35 used, results in uneven breaking of the points, and a consequent difference in the intensity of the sparks formed at the engine spark-plugs. This unevenness, as will be evident, has been eliminated by my improved 40 construction.

The breaker arms are of course connected or interposed in the circuit of the distributor

and ignition system. In the present showing that arm 4 which is insulated from the casing wall 2 is connected as by a screw 13 to a collecting ring 14 mounted in the casing on the side of the wall 2 opposite from the arms 4 while the other arm, as stated, is connected direct to the wall and casing, which is grounded. 45 50

It is evident, however, that my breaker construction may be mounted in any distributor or timer, and the particular parts to which the arms are electrically connected depends of course upon the construction of 55 said distributor.

From the foregoing description it will be readily seen that I have produced such a device as substantially fulfills the objects of the invention as set forth herein. 60

While this specification sets forth in detail the present and preferred construction of the device still in practice such deviations from such detail may be resorted to as do not form a departure from the spirit of the 65 invention, as defined by the appended claim. 70

Having now particularly described my invention what I claim as new and useful and desire to secure by Letters Patent is:

A breaker mechanism for distributors including a pair of parallel spring arms fixed at one end and tending to spring toward each other, symmetrical inward bends in the arms terminating in free ends parallel to the arms, contact points in such free ends normally in contact with each other under the influence of the spring action of the arms, and a means co-operating with the arms to intermittently engage and spread the arms to cause the points to break contact with each other. 75 80

In testimony whereof I affix my signature.

PAUL E. DEMMER.
